WORK POSITIONING GUIDE

John G. Wright, James M. Chafin, Eugene Sudan, and Charles A. Watkins, Atlanta, and John A. Hanson, College Park, Ga., assignors to The Auto-Soler Company, a corporation of Georgia

Original application September 8, 1947, Serial No. 722,824. Divided and this application December 13, 1950, Serial No. 208,222

2 Claims. (Cl. 1-19)

1

This invention relates to fastener forming and inserting machines of the type in which fasteners are formed from a continuous length of wire or the like and inserted in material to be secured. This is a division of our copending application Serial No. 722,824, filed September 8, 1947, and issued as U. S. Letters Patent No. 2,566,104, on August 28, 1951.

The machine of the present invention is particularly adapted for soeling shoes, and has features in common with the machine disclosed in the copending application of Wright et al., Ser. No. 595,766, filed May 25, 1945, and issued as U. S. Letters Patent No. 2,520,521, on August 29, 1950. As in the case of the above copending application, the present machine may also be modified for use in woodworking operations, and differs over the machine disclosed in the prior application in the incorporation of improved operating elements which provide substantial structural and operating advantages as described more in detail below.

The present invention is illustrated, with particular reference to the above mentioned improved features, in the accompanying drawing, in which:

Fig. 1 is a front elevation, partly cut away, of a fastener forming and inserting machine constructed in accordance with the present invention;

Fig. 2 is a corresponding side elevation;

Fig. 3 is a fragmentary side elevation of the guide means provided for positioning material to be secured in relation to the machine of the present invention;

Fig. 4 is a plan detail, mainly in section, illustrating the arrangement of the extending guide arm of the guide means shown in Fig. 3;

Fig. 5 is a corresponding detail showing the adjusting elements of the guide means positioned for varying the disposition of the extending guide arm;

Fig. 6 is a transverse sectional detail showing further the arrangement of the adjusting elements for the extending guide arm; and

Fig. 7 is a sectional detail taken substantially on the line 7—7 in Fig. 6.

Referring first to Figs. 1 and 2 of the drawing, the fastener forming and inserting machine shown comprises a suitable frame structure 100 made up of a vertically extending base portion 101 adapted to support the machine on a floor or similar surface, and an upper frame section 102 carried at the upper extending end of the base portion 101. The upper frame section 102 is ar-

2

ranged to support an operating head 103 and an associated plunger mechanism 104 adapted for cyclic actuation of a knife assembly, indicated generally at 600, for fastener forming and fastener inserting operations as described in our above noted copending application Serial No. 772,824.

The plunger mechanism 104 comprises a plunger 105 carried in a crossarm 106 which is mounted to extend from an operating rod 107 supported for reciprocating movement by the upper frame section 102. The operating rod 107 extends downwardly to the base portion 101 for association with a connecting arm 108 which is actuated from a crank mechanism at 109 driven by a motor unit 110. The motor unit 110 may be equipped for operation with conventional electrical connections (not shown) arranged through a conveniently disposed switch box as at 111. A clutch mechanism 112 is interposed between the motor unit 110 and the crank mechanism 109, and is arranged for actuation from a foot pedal 113. This arrangement is such that depression of the foot pedal 113 results in actuation of the clutch mechanism 112 to connect the motor unit 110 for driving the crank mechanism 109 with consequent reciprocation of the operating rod 107 through connecting arm 108. A motor unit and related operating elements of the type just described above are also incorporated in the fastener forming and inserting machine disclosed in the above identified copending application Serial No. 595,776, and reference is made to that application for further details.

35. The upper frame section 102 also supports a wire mounting reel 114 from which wire 115 for forming fasteners is trained through a tubular guide 116 to the operating head 103, and a lever arm assembly 500 arranged for actuation by the plunger mechanism 104 for feeding the wire 115 from reel 114 to the operating head 103. In addition, the upper frame structure 102 supports a guide means 800 for positioning material to be secured in relation to said machine, as described further below; and a work support 117 such as is disclosed in our above identified copending application Serial No. 595,776.

The guide means 800, which is illustrated in detail in Figs. 3 to 6 of the drawing is of the same general type as disclosed in the above copending application, and in United States Patent 2,315,382, issued March 30, 1943, to Ajouelo et al. but incorporates an improved arrangement for adjustment of the guide means.

55. As described in the above noted prior appli-

cation and patent, the guide means 800 comprises a bracket member 801 pivotably mounted on the upper frame structure 102 and adapted to assume several positions for guiding material on the work-support 117 in relation to the operating head 103, or swing to a retracted position when not in use. The bracket member 801 which is adapted for functioning in this manner in accordance with the previous disclosures, is further arranged to carry an extending guide 10 arm 802 for sliding movement in association with means for adjusting the extending disposition of the guide arm 802 and locking it in place when adjusted. The guide arm 802 is formed with beveled edges 803 to fit correspondingly undercut grooves 804 in the bracket member 801 which accommodate the guide arm 802 for sliding movement on the bracket member 801. The guide arm 802 is further formed with a toothed portion in the nature of a rack as shown most clearly at 805 in Fig. 3. A shaft member 806 is also carried by the bracket member 801 for sliding movement transversely with respect to the guide arm 802, and shaft member 806 also has a toothed portion 807 forming a pinion disposed for engagement with the rack portion 805 on guide arm 802. A pawl member 808 is yieldingly positioned by a spring 809 in bracket member 801 for normally engaging the pinion 807 (see Fig. 3) to lock it against rotation, and consequently lock the guide arm 802 in a corresponding extended position.

To release the pinion 807 for adjustment of the guide arm 802, the shaft member 806 is fitted with a cam 810 adapted to displace the pawl member 808. As mentioned above, the shaft member 806 is carried for sliding movement in the bracket 801, bearing portions 811 being journaled in the bracket 801 so that the shaft member 806 may rotate or slide transversely as desired. A pin 812 is fitted in the bracket 801 between the bearing portions 811 to prevent removal of the shaft member 806 and provide a stop in inactive position as shown in Fig. 4. The cam 810 is carried on the shaft member 806 adjacent the pinion 807, and takes the general form of a collar cut away to form a flat face at 813 which seats under the guide arm 802 so that rotation of the cam 810 with shaft member 806 is prevented. The cam 810 has a beveled cam surface at 814 adapted to contact a similar bevel 815 on pawl member 808 and displace it when the shaft member 806 is translated to adjusting position as shown in Fig. 6. Accordingly, by shifting the shaft member 806, the extending 55 guide arm 802 may be easily adjusted or locked

in position as desired to facilitate fastener forming operations being carried out on the machine. The shaft member 806 is fitted with an adjusting knob 816 at its extending end, which is preferably marked as indicated at 817 to provide for gauging the adjusted position of guide arm 802.

We claim:

1. In a fastener forming and inserting machine adapted for forming fasteners from a continuous length of wire and inserting said fasteners in material to be secured, a guide means for positioning said material to be secured comprising a bracket member mounted on said machine, an extending guide arm carried for sliding movement by said bracket member, said guide arm being formed with a toothed portion in the nature of a rack, a shaft member carried by said bracket member for sliding movement transversely with respect to said guide arm, said shaft member having a toothed portion forming a pinion disposed for engagement with the rack portion of said guide arm, a pawl member yieldingly positioned on said bracket member for normally locking said pinion against rotation whereby said guide arm may be maintained at a fixed extending position, and a cam element carried on said shaft member for displacement of said pawl member upon sliding movement of said shaft member whereby said pinion may be released for rotation to adjust the extending position of said guide arm.

2. A guide means for positioning work material in a fastener forming and inserting machine, said guide means comprising an extending guide arm slidably mounted on said machine for adjustment of its extending disposition, an adjusting shaft member mounted on said machine for rotation and for sliding movement transversely with respect to said guide arm, said shaft member being connected in geared relation with said guide arm, yieldable means carried on said machine for normally locking said shaft member against rotation, and cam means carried by said shaft member for displacing said yieldable locking means upon sliding movement of said shaft member to allow adjustment of the extending disposition of said guide arm by rotation of said shaft member.
